UNITED STATES PATENT OFFICE.

THOMAS W. HOLT, OF ELKHART, INDIANA, ASSIGNOR, BY MESNE ASSIGNMENTS, TO THE ADAMS & WESTLAKE COMPANY, OF CHICAGO, ILLINOIS, A CORPORATION OF ILLINOIS.

SASH GUIDE.

Original application filed May 25, 1925, Serial No. 32,536. Divided and this application filed October 9, 1926, Serial No. 140,540.

The object of the present invention is to provide an improved sash guide of the type adapted to fit within a grooved sash stile, which guide is simple and inexpensive to manufacture, and will afford a snug weatherproof closure for the sash with which associated.

For the purpose of exemplification, one structural form of the invention is presented herein, but other slightly modified forms are of course contemplated.

In the accompanying drawing:

Fig. 1 is a view of a corner of a window sash associated with a guide constructed in accordance with the invention;

Fig. 2 is a front view of the guide;

Fig. 3 is a side view of the same;

Fig. 4 is a transverse section taken through the sash and guide at one point; and

Fig. 5 is a similar section, taken at another point.

The guide is shown in the drawing as attached to the jamb 10 of a window frame and as embraced between the side walls 11 of a groove in the stile 12 of a window sash. The guide includes a rigid channel strip 13, which is secured to the jamb 10 by a plurality of screws 14 with the base 15 of the strip seated against a strip 16 of compressible weatherproof material interposed between the guide and the jamb.

A number of leaf springs 17 are secured to one side wall 18 of the strip and bow laterally through apertures in the other side wall 19 into spring pressed engagement with one of the side walls 11 of the groove in the stile of the sash. A number of other leaf springs 20 are secured to the base 15 of the strip between the springs 17 and bow outwardly from the channel in the strip into spring-pressed engagement with the base 21 of the groove in the stile of the sash.

A folded strip 22 of resiliently yieldable fabric or other suitable material is secured within the channel in the strip against the side wall 19 thereof, and projects outwardly from the channel into continuous engagement with the base 21 of the groove throughout the length thereof.

It will be understood from the foregoing that the springs 17 engage with one of the side walls 11 of the groove in the stile of

the sash and press the other side wall of the groove resiliently against the side wall 18 of the strip to produce a weather-proof joint along the same, that the springs 20 engage with the base 21 of the groove to center the sash between the two sash guides on the opposed jambs of the window frame, and that the strip 21 bears continuously in a weatherproof joint against the base 21 of the groove; thereby affording a thoroughly sealed but resiliently yieldable and easily slidable association between the sash and the guide.

This application is a division of my co-pending application Serial No. 32,536 filed May 25, 1925.

I claim:

1. The combination with a sash having a groove in the stile thereof, of a guide comprising a channel strip adapted to be attached to a window jamb and contained within the groove, a plurality of spring-pressed sash-engaging elements projecting laterally from one side of the strip against one side of the groove for pressing the other side of the groove against the other side of the strip, and a plurality of other spring-pressed sash-engaging elements projecting outwardly from the channel against the bottom of the groove.

2. A sash guide, comprising a rigid channel strip adapted to be attached to a window jamb, and a strip of resiliently flexible weather-proofing material secured within the channel and projecting outwardly therefrom.

3. A sash guide, comprising a rigid channel strip adapted to be attached to a window jamb, a plurality of spring-pressed sash-engaging elements projecting laterally through apertures in one side of the strip, and a strip of resiliently flexible weather-proofing material secured within the channel and projecting outwardly therefrom.

4. A sash guide, comprising a rigid channel strip adapted to be attached to a window jamb, a plurality of spring-pressed sash-engaging elements projecting outwardly from the channel in the strip, and a strip of resiliently flexible weather-proofing material secured within the channel and projecting outwardly therefrom.

5. A sash guide, comprising a rigid channel strip adapted to be attached to a window jamb, a plurality of spring-pressed sash-engaging elements projecting laterally through apertures in one side of the strip, a plurality of other spring-pressed sash-engaging elements projecting outwardly from the channel in the strip, and a strip of resiliently flexible weather-proofing material secured within the channel against the apertured side of the strip and projecting outwardly therefrom.
10. 6. A sash guide, comprising a channel

strip adapted to be attached to a window jamb, a strip of resiliently compressible 15 weather-proofing material interposed between the channel strip and the jamb, means for drawing the channel strip toward the jamb to compress the weather-proofing strip, and means associated with the channel strip 20 for effecting a weather-proof closure between the same and the associated sash throughout the length thereof.

In testimony whereof I have hereunto subscribed my name.

THOMAS W. HOLT.
